FREDERICK H. VALITON, OF DEER LODGE, MONTANA, ASSIGNOR OF ONE-HALF TO
PHILIP L. O'NEILL, OF DEER LODGE, MONTANA.

MISS DETECTOR FOR INTERNAL-COMBUSTION ENGINES.

Application filed November 22, 1922. Serial No. 602,546.

To all whom it may concern:

Be it known that I, FREDERICK H. VALITON, a citizen of the United States, and resident of Deer Lodge, in the county of Powell and State of Montana, have invented certain new and useful Improvements in Miss Detectors for Internal-Combustion Engines, of which the following is a specification.

This invention relates to detectors especially adapted for use on internal combustion engines.

Briefly stated an important object of this invention is to provide a detector for internal combustion engines having simple and reliable means whereby to electrically or mechanically indicate to the operator the particular cylinder of the engine which is misfiring.

A further object of the invention is to provide a detector of the character described which may be applied to an internal combustion engine of one or more cylinders without materially altering the construction of the engine and without impairing the operation of the same.

A further object of the invention is to provide a detector for internal combustion engines which is of highly simplified construction, neat in appearance and cheap to manufacture.

Other objects and advantages will be apparent during the course of the following description.

In the accompanying drawings, forming a part of this application, and in which like numerals are employed to designate like parts throughout the same,

Figure 1 is a fragmentary side elevation of the improved detector applied to an internal combustion engine, the exhaust manifold of the engine being shown partly in section.

Figure 2 is a vertical transverse sectional view through the detector applied.

Figure 3 is a front elevation of a modified form of invention, parts being shown in section and a wiring diagram being shown in conjunction with the detector.

Figure 4 is a side elevation of the form of invention illustrated in Figure 3.

Figure 5 is a detail horizontal sectional view taken on line 5—5 of Figure 3.

Figure 6 is a perspective illustrating the application of the electrical indicator and the switch therefor.

Figure 7 is a vertical transverse sectional view through the electric indicator and the switch.

Figure 8 is a wiring diagram employed in connection with the invention.

In the drawing wherein for the purpose of illustration is shown a preferred embodiment of the invention the numeral 5 designates a body formed from stamped metal or the like and being approximately in the form of a triangle. Figure 1 illustrates that the lower portion of the body 5 is formed with a plurality of disk-shaped extensions formed with openings surrounded by bosses 6. The bosses 6 are confined between the exhaust ports 8 and the exhaust manifold 9 so that suitable gaskets 7 may be employed to provide a gas tight connection between the parts. By reason of locating the said openings in alignment with the exhaust ports 8 and manifold 9 the burned and unburned fuel will pass through the openings and into the exhaust manifold.

In carrying out the invention as illustrated in Figures 1 and 2, a plurality of rods 10 or shafts are extended through the upper portions of the bosses and are extended into sockets in the lower portion of the bosses whereby the shafts are rotatably supported. It may be stated that the body 5 is provided adjacent its upper portion with a plurality of struck-out bearings 11 which rotatably receive the upper portions of the shafts 10. Therefore the upper portions of the shafts 10 are rotatably supported by the struck-out portions 11 while the lower portions of the shafts are rotatably supported by the several bosses 6.

Figures 1 and 2 plainly illustrate that the lower portions of the shafts 10 are provided with semi-circular exhaust contact wings 14 normally held at right angles to the path of travel of the products of combustion and the unburned fuel by means of coiled springs 15 anchored to the shafts 10 and to the adjacent struck-out portions or bearing members 11.

The tension of the springs 15 is sufficient to overcome the force of the unburned exhaust fuel if any and the contact wings are therefore turned only as the result of engagement with the burned fuel when the motor is accelerated.

When the wings 14 are turned a quarter of a turn as a result of contact with the

burned fuel of a high velocity the shafts 10 are also turned and an indicator head 16 carried by the upper portion of each shaft is turned within an opening 17 in the upper portion of the body 5. Figure 1 illustrates that each spring 15 normally holds the associated indicator head 16 in engagement with a stop lug 18 carried by one edge of the opening 17. By reason of this arrangement the turning of the rod 10 beyond a predetermined degree is prevented. That is to say the heads 16 which correspond in number to the number of cylinders normally lay parallel to the body 5.

In the use of this form of the invention the several bosses 6 and the gaskets 7 are clamped between the exhaust ports of the engine and the exhaust manifold so that the wings 14 will be arranged at right angles to the path of travel of the exhaust. Should any particular spark plug fail to fire at the proper time the compressed fuel will not be ignited and will pass out through the exhaust port, when the exhaust valve is open, leaving the wings 14 in their original positions due to the tension of the spring 15.

When it is desired to make a test, the engine is accelerated and the burned fuel or products of combustion in entering the exhaust manifold will strike the wings 14 and turn the same a quarter of a turn. This, of course, turns the shafts 10 and the heads 16 against the tension of the coil springs whereupon the operator by observing the heads 16 will immediately know which cylinders are firing and which are not. Those cylinders which are not firing will exhaust an unburned fuel, the force of which will be insufficient to turn the wings 14 which they encounter. Therefore the heads 16 which are turned a quarter of a turn will indicate to the operator that the cylinders which they represent are properly firing and in case any of the heads 16 remain in their original position the operator will be advised that the cylinders which they represent are not firing properly.

It is understood, of course, that the several cylinders are numbered and that numbers corresponding to the number of cylinders may be placed on the sheet metal plate 5 so as to relieve the operator of the necessity of tracing the shaft 10 to the proper cylinder.

In carrying out the invention the several indicators may be manufactured entirely independent of each other and installed separately for each cylinder. It will be observed that each wing 14 is formed from a disk-shaped piece of metal bent upon itself intermediate its ends to provide a pair of semi-circular portions and an attaching member which receives the lower portion of the stem. Such fastening devices as rivets may be employed for connecting the semi-circular por-

tions of the head and the said fastening devices also secure the contact wing to the shaft.

In the modified form of the invention the numeral 30 designates a body or supporting member having its lower portion thickened to provide a boss 31 adapted to be clamped between the exhaust port and the exhaust manifold. Suitable gaskets 32 are arranged between the boss 31 and the manifold and the engine whereby to provide a gas-tight connection between the parts. In this case a semi-circular exhaust contact wing 33 is arranged in the opening defined by the boss and a spindle or shaft 34 is rigidly connected to the wing, the said spindle being rotatably connected to opposite sides of the boss 31 and having its upper portion formed with a target or disk-shaped indicator head 35. The disk-shaped indicator head 35 visually indicates to the operator when the wing 33 is turned as a result of contact with the unburned fuel.

In this form of the invention a secondary wing 38 is provided and the same is of arcuate formation and is of such an area and so arranged that it is operated only by the heavy exhaust gases which result from the firing of the compressed fuel. That is to say the tension behind the secondary wing 38 prevents the wing from being operated as the result of contact with the unburned fuel, which as previously stated, is sufficient to operate the wing 33. When the engine is operated and one of the cylinders is improperly firing, the unburned fuel will contact with the wing 33 and turn the same and this unburned fuel will not turn the wing 38.

However, assuming that the engine is operating at a considerable speed and all the cylinders are firing, the exhaust gases will turn both the wings 33 and 38 simultaneously and the tubular shaft 40 which is rigidly connected to the secondary wing 38 will also be turned.

Figure 3 illustrates that the tubular shaft 40 which receives the shaft 34 is provided with a target 42. The outer target 42 which is of annular formation carries a laterally projecting arm 43 having a contact 44 which is engaged by a spring contact 45 carried by the indicator 35. When the wings 33 and 38 are operated simultaneously as a result of the high speed of the engine the indicators 35 and 42 will be turned together and the members 44 and 45 will be maintained in spaced relation.

However assuming that the cylinder is misfiring the unburned fuel will contact with the wing 33 and cause the wing alone to turn. The velocity of the unburned fuel and the pressure of the same will be insufficient to operate the arcuate exhaust contact member 38. When this occurs the con-

tact spring 45 will engage the contact 44 and therefore close an electrical circuit for indicating at a remote point that the engine is operating improperly.

5 In carrying out the invention the outer or secondary contact member 38 is normally held in a set position by means of a coiled spring 50 anchored to the tubular shaft 40 and having its upper portion anchored 10 to the struck out portion or lip 53 formed on the upper portion of the body 30.

The struck out lip 53 not only forms an anchoring means for the lower spring 50 but also serves as a bearing for the tubular 15 shaft 40. Furthermore by cutting out a portion of the body to provide the struck out lip 53 an opening is provided to partially receive the spring 50.

The contact member 33 is normally held 20 in an inoperative position solely by means of a coil spring 60 anchored at its lower end to an insulated terminal member 65. The other end of the coil spring 60 is anchored to the inner portion of the contact leaf 25 spring 45. However, the spring 60 is insulated from the head 35 and all other parts except the members 45 and 65.

Figure 2 illustrates that the contact 65 has electrical connection with one of a plurality of bulbs 70 through the medium of an electrical wire 72 so that when one of the contacts 44 and 45 are engaged with each other the current will pass through the bulb for lighting the same and thereby indicate to the operator that the cylinder is 30 misfiring. A bracket 87 is formed integral with the body 30 and engages the rear side of the heads 35 and 42 so as to limit the movement of the same under the influence 40 of the associated coiled springs.

The several electric bulbs 70 which correspond in number to the number of cylinders are mounted in sockets 79 carried by a cup-shaped support 167. The cup-shaped 45 support 167 is provided with a continuous branch 168 which may be secured to the rear side of the instrument board 169 by fastening bolts 170 of any desired type. Suitable hoods or shades 173 surround the several 50 bulbs 70 so that the light from each bulb is discharged only through the associated opening 176. In this manner the operator is accurately advised as to which bulb is shining and which is not.

55 A switch 180 is carried by the instrument board and has connection with the wires of the circuit and one terminal of the switch is connected to one pole of the ammeter 181, the said ammeter having connection with the battery 182 through the medium of an electric wire 183. One pole of the battery is grounded as indicated at 184. As previously stated the contact spring 45 is insulated from, but fastened to the head 35. The 60 spring 60 has its upper portion fastened to

the contact spring 45 and its lower portion fastened to the insulator terminal 65. This leaves the spring 60 and the contact 45 insulated from all other parts. Therefore the spring 60 is used as a means of conducting 70 the current to the contact spring 45.

Should the cylinder that the detector represents misfire the wing 33 will be turned until the contact spring 45 comes into engagement with the contact 44 on the arm 43. 75 Current will then flow from the battery which for automobile work has one terminal grounded through the ammeter, through the switch, through the light designating the misfiring cylinder, through the insulator 80 terminal 65, the insulated spring 60, through the spring contact 45, the contact point 44, and the arm 43 where it is grounded.

In operation should the speed of the engine be increased or the engine be subjected 85 to an unusual load, the heavy exhaust gases will not only turn the wing 33 but will turn the secondary exhaust contact wing 38 and this will maintain the contacts 44 and 45 in spaced relation. For this reason the circuit 90 will not be completed and the lights will not burn.

Of course the electrical part of the form of the invention illustrated in Figures 2 to 8 may be dispensed with and the operator 95 may by observing the heads 35 and 42 ascertain which cylinders are improperly firing. Furthermore the electrical indicator may be employed in connection with the form of the invention illustrated in Figures 100 1 and 2.

The foregoing illustrates that the invention forming the subject matter of this application is capable of a wide variety of mechanical expressions and it is therefore 105 understood that the several forms of the invention herewith shown and described are to be taken as preferred examples of the same and that such minor changes in arrangement and construction of parts may be 110 made as will remain within the spirit of the invention and the scope of what is claimed.

Having thus described the invention, what is claimed is:—

1. A miss-detector for internal combustion engines comprising a body having apertures adapted to be arranged in registration with the exhaust ports of an internal combustion engine, contact wings having shafts rotatably connected to the body, 115 spring means to normally hold the wings at right angles to the path of travel of the exhaust, and indicators carried by said shaft.

2. A miss-indicator for internal combustion engines comprising a body having a boss and an opening within the boss, a shaft rotatably carried by said boss and having an indicator wing arranged within the opening and at right angles to the path of travel of the exhaust, said body being pro- 125 130

vided with a lip having an opening rotatably receiving said shaft, a disk-shaped head connected to said shaft and constituting a visual indicator, and means limiting the turning of said wing in one direction.

3. A miss-indicator for internal combustion engines comprising a body having a boss and an opening within the boss, a shaft rotatably carried by said boss and having an indicator wing arranged within the opening, said body being provided with a lip having an opening rotatably receiving said shaft, a disk-shaped head connected to said shaft and constituting a visual indicator, and a spring anchored to the shaft and connected to said lip whereby to urge the wing to its inoperative position.

4. A miss-detector for internal combustion engines comprising a body, a shaft rotatably supported by said body and having an exhaust contact wing arranged in the path of travel of the exhaust, an indicator head connected to said shaft, a second shaft of tubular formation receiving the first named shaft and having a second exhaust contact wing, a second indicator head connected to said second named shaft, and cooperating means carried by said first and second named heads to indicate when the engine is misfiring.

5. A miss-detector for internal combustion engines comprising a body, a shaft rotatably supported by said body and having an exhaust contact wing arranged in the path of travel of the exhaust, an indicator head connected to said shaft, a second shaft of tubular formation receiving the first named shaft and having a second exhaust contact wing, a second indicator head connected to said second named shaft, cooperating means carried by said first and second named heads to indicate when the engine is misfiring, and a bracket limiting the rotation of said first and second-named heads.

6. A miss-detector for internal combustion engines comprising a body, a shaft rotatably supported by said body and having an exhaust contact wing arranged in the path of travel of the exhaust, an indicator head connected to said shaft, a second shaft of tubular formation receiving the first named shaft and having a second exhaust contact wing, a second indicator head connected to said second named shaft, cooperating means carried by said first and second named heads to indicate when the engine is misfiring, and a pair of springs independently urging said wings to their inoperative positions.

7. A miss-indicator for internal combustion engines comprising a body, a shaft rotatably supported by said body, a wing carried by said shaft, a second wing of arcuate formation having a tubular shaft rotat-

ably receiving said first named shaft, an indicator head connected to said first named shaft, a second head connected to said second named shaft, said first and second named heads being provided with members adapted for engaging as the result of the turning of one exhaust contact wing with relation to the other wing, and springs independently urging said wings to positions at right angles to the path of travel of the exhaust, 75 said wings being in the path of travel of the exhaust.

8. A miss-indicator for internal combustion engines comprising a body, a shaft rotatably supported by said body, a wing carried by said shaft, a second wing of arcuate formation arranged adjacent said first named shaft and having a tubular shaft rotatably receiving said first named shaft an indicator head connected to said first named shaft, a second head connected to said second named shaft, said first and second named heads being provided with laterally projecting members adapted for engaging as the result of the turning of one 85 exhaust contact wing with relation to the other wing, springs independently urging said wings to positions at right angles to the path of travel of the exhaust, and a bracket limiting the rotation of the wings, said 95 wings being in the path of travel of the exhaust.

9. A miss-indicator comprising a body having a plurality of openings adapted for the passage of the exhaust from the cylinders of an internal combustion engine, pairs of wings arranged in said openings, and indicator heads having connection with said wings, one indicator of each pair being movable with relation to the other indicator of 105 that pair.

10. A miss-indicator comprising a body having a plurality of openings adapted for the passage of the exhaust from the cylinders of an internal combustion engine, wings arranged in said openings, indicator heads having connection with said wings, and spring means for positioning the wings at right angles to the path of travel of the exhaust.

11. A miss detector for engines comprising a body, a pair of wings arranged in the path of travel of the exhaust from a particular cylinder and being separately operated, shafts operated by said wings and 110 having indicators, and cooperating means operated by the movement of one of said indicators with relation to the other indicator to indicate when a particular cylinder is misfiring.

12. A miss detector for internal combustion engines comprising a pair of wings arranged in the path of travel of the exhaust from an internal combustion engine, shafts supporting the wings and having separate 120

indicators, and separate springs associated with said shafts and urging the wings separately to positions at right angles to the path of travel of the exhaust, one of said indicators being adapted to move with relation to the other indicator to indicate the misfiring of the engine.

13. A miss detector for internal combustion engines comprising a pair of wings arranged in the path of travel of the exhaust from an internal combustion engine, shafts supporting the wings and having separate indicators, separate springs associated with said shafts and urging the wings separately

to positions at right angles to the path of travel of the exhaust, said shafts being interfitting, the movement of one indicator with relation to the other indicator constituting a means to indicate when a cylinder is misfiring.

14. A miss detector comprising an exhaust operated wing having an indicator, spring means urging the wing to a position approximately at right angles to the path of travel of the exhaust, and a body supporting the wing and having a stop limiting the turning of said wing.

FREDERICK H. VALITON.
